UNITED STATES PATENT OFFICE

168,379

CHRISTMAS TREE HOLDER

Joseph E. Scanland, Des Moines, Iowa, assignor
 to New Monarch Machine and Stamping Co.,
 Des Moines, Iowa, a corporation of Iowa

Application August 11, 1951, Serial No. 16,242

Term of patent 14 years

(Cl. D35—3)

To all whom it may concern:

Be it known that I, Joseph E. Scanland, a citizen of the United States and a resident of the city of Des Moines, county of Polk, State of Iowa, have invented a new, original, and ornamental Design for a Christmas Tree Holder, of which the following is a specification, reference being had to the accompanying drawing, forming a part thereof, in which:

Figure 1 is a perspective view of a Christmas tree holder, showing my new design;

Figure 2 is a plan elevational view thereof; and Figure 3 is a side elevational view thereof.

I claim:

The ornamental design for a Christmas tree holder, substantially as shown.

JOSEPH E. SCANLAND.
